[57] CLAIM

The ornamental design for a removable screen for a
vehicle window, as shown and described.

DESCRIPTION

FIG. 1 is a perspective view of a removable screen for
a vehicle window showing my new design;
FIG. 2 is a bottom plan view thereof;
FIG. 3 is a left end elevation view thereof;
FIG. 4 is a right end elevation view thereof;
FIG. 5 is an elevation view of the side opposite to that
shown in FIG. 1;
FIG. 6 is a perspective view of a removable screen for
a vehicle window showing a second embodiment of my
new design;
FIG. 7 is a bottom plan view of FIG. 6;
FIG. 8 is a left end elevation view of FIG. 6;
FIG. 9 is a right end elevation view of FIG. 6; and
FIG. 10 is an elevation view of the side opposite to that
shown in FIG. 6.
